US00D777180S

(12) **United States Design Patent** (10) Patent No.: **US D777,180 S**
(45) Date of Patent: ** Jan. 24, 2017

(54) **TV RECEIVER WITH GRAPHICAL USER INTERFACE**

(71) Applicant: **LG ELECTRONICS INC.**, Seoul (KR)

(72) Inventors: **Uniyoung Kim**, Seoul (KR); **Hyeran Jang**, Seoul (KR)

(73) Assignee: **LG Electronics Inc.**, Seoul (KR)

(**) Term: **15 Years**

(21) Appl. No.: **29/537,389**

(22) Filed: **Aug. 25, 2015**

(30) **Foreign Application Priority Data**

Feb. 25, 2015 (KR) 30-2015-0009570

(51) **LOC (10) Cl.** **14-04**

(52) **U.S. Cl.**

USPC **D14/485**

(58) **Field of Classification Search**

USPC D14/485-488

CPC . G06F 3/0482; G06F 3/04842; G06F 3/04817

See application file for complete search history.

(57) **CLAIM**

The ornamental design for a TV receiver with graphical user interface, as shown and described.

DESCRIPTION

The FIGURE is a front view of a TV receiver with graphical user interface showing our new design.

The broken lines showing the TV receiver form no part of the claimed design.

1 Claim, 1 Drawing Sheet
